UNITED STATES PATENT OFFICE.

ZACHARY T. JONES, OF NEW YORK, N. Y.

DESIGN FOR A CORNER-POST FOR BEDSTEADS.

SPECIFICATION forming part of Design No. 24,973, dated December 10, 1895.

Application filed October 3, 1895. Serial No. 564,565. Term of patent 7 years.

To all whom it may concern:

Be it known that I ZACHARY TAYLOR JONES, a citizen of the United States, residing in the city of New York, in the county and State of New York, have invented and produced a new and original Design for Corner-Posts for Bedsteads, of which the following is a specification, reference being had to the accompanying drawings, which form a part hereof.

Figure 1 of the drawings represents in perspective a corner-post which embodies my design. Fig. 2 is a detail view intended to show somewhat more clearly the relations of parts of the design.

My design consists in a vertically-elongated polygonal body, having salient ribs or beads at the vertical meeting edges of the faces of the body.

The body A of the post is polygonal, as represented in Figs. 1 and 2. At the meeting edges of the vertical faces of the body are ribs or beads B, which stand out strongly, one at each corner of the post, as indicated in Fig. 2.

What I claim, and desire to secure by Letters Patent, is—

The design for a corner post for a bedstead, substantially as shown and described.

This specification signed and witnessed this 1st day of October, A. D. 1895.

ZACHARY T. JONES.

In presence of—

W. B. GREELEY,
ALFRED W. KIDDLE.
